US00D763940S

(12) **United States Design Patent**
Bourque et al.

(10) **Patent No.:** **US D763,940 S**
(45) **Date of Patent:** **** Aug. 16, 2016**

(54) **HANDHELD ELECTRONIC MAGNIFIER FOR LOW VISION USERS**

(71) Applicant: **TECHNOLOGIES HUMANWARE INC.**, Drummondville (Québec) (CA)

(72) Inventors: **Georges Bourque**, Montréal (CA); **Luc Blanchette**, Montréal (CA); **Éric Lapointe**, Montréal (CA); **David Gagné**, Montréal (CA)

(73) Assignee: **TECHNOLOGIES HUMANWARE INC.** (CA)

(**) Term: **14 Years**

(21) Appl. No.: **29/488,418**

(22) Filed: **Apr. 18, 2014**

(51) LOC (10) Cl. **16-06**

(52) U.S. Cl.

USPC **D16/135**

(58) **Field of Classification Search**

USPC D6/300; D12/193; D14/203.3–203.7, D14/217, 238.1, 240, 248, 250–253, D14/341–347, 440, 444, 447, 496; D16/130, 134, 135; 348/63, 240.2; 359/802, 803, 807, 808, 809, 810, 811, 359/813

(57) **CLAIM**

The ornamental design for a handheld electronic magnifier for low vision users, as shown and described.

DESCRIPTION

FIG. 1 is a front perspective view of a first variant of the article;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a front perspective view of a second variant of the article;

FIG. 9 is a front elevation view thereof;

FIG. 10 is a rear elevation view thereof;

FIG. 11 is a right side elevation view thereof;

FIG. 12 is a left side elevation view thereof;

FIG. 13 is a top plan view thereof;

FIG. 14 is a bottom plan view thereof;

FIG. 15 is a front perspective view of a third variant of the article;

FIG. 16 is a front elevation view thereof;

FIG. 17 is a rear elevation view thereof;

FIG. 18 is a right side elevation view thereof;

FIG. 19 is a left side elevation view thereof;

FIG. 20 is a top plan view thereof; and,

FIG. 21 is a bottom plan view thereof.

The broken lines in the drawings depict portions of the handheld electronic magnifier for low vision users that form no part of the claimed design.

1 Claim, 15 Drawing Sheets
